(57) **CLAIM**

An ornamental design for a pair of earbuds, as shown and described.

DESCRIPTION

FIG. 1 is a first perspective view of a pair of earbuds showing our new design;

FIG. 2 is a second perspective view;

FIG. 3 is a first side view shown in FIG. 1;

FIG. 4 is a second side view in FIG. 1, the second side being opposite the first side shown in FIG. 3;

FIG. 5 is a top view shown in FIG. 1;

FIG. 6 is a bottom view shown in FIG. 1;

FIG. 7 is a front view shown in FIG. 1; and,

FIG. 8 is a rear view shown in FIG. 1.

The broken lines depict environmental structure and form no part of the claimed design. The shade lines in the Figures show surface contour and not surface ornamentation.
